UNITED STATES PATENT OFFICE.

WILLIAM DE HART, OF AMSTERDAM, ASSIGNOR TO JOSIAH BARBER & SONS,
OF AUBURN, NEW YORK.

DESIGN FOR A CARPET-PATTERN.

Specification forming part of Design No. 5,837, dated May 7, 1872.

Specification describing a new and original Design for a Carpet, invented by WM. DE HART, of Amsterdam, Montgomery county, New York.

The accompanying photograph fully illustrates my new design.

This invention relates to a new carpet-design, comprehending three several items, to wit:

First, a square figure, with zigzag edge and checkered border, and ornamental center, as shown. Secondly, a larger main figure, with straight sides and ends and rounded corners, with ornamental tufts in the ends, while the

above-mentioned zigzag edged square figure enters its side, as shown. The center of the main figure is formed by an ornamental lozenge-shaped design. Thirdly, the invention consists of a new floral design interposed between the main figures, as shown.

I claim as my invention—

The design for a carpet, containing the two main figures and the floral design, as shown.

WILLIAM DE HART.
